2 SHEETS—SHEET 2.

UNITED STATES PATENT OFFICE.

CHARLES FISK, OF FLUSHING, NEW YORK.

BARREL-FILLER.

1,400,275.

Specification of Letters Patent. Patented Dec. 13, 1921.

Application filed December 30, 1919. Serial No. 348,364.

To all whom it may concern:

Be it known that I, CHARLES FISK, a citizen of the United States, and a resident of Flushing, in the county of Queens and State 5 of New York, have invented certain new and useful Improvements in Barrel-Fillers, of which the following is a specification.

The invention pertains to receptacle or 10 barrel filling mechanisms equipped with automatically acting means for cutting off the flow of liquid into the barrel when the liquid therein has attained the requisite level.

Barrel fillers, so designated, are generally 15 well known and have many features in common.

One object of my invention is to provide a barrel filler possessing novel features of construction rendering the device certain in 20 operation and capable of ready manufacture both as to its details and the assembly of its parts.

A further object of the invention is to provide a barrel filler whose parts are of such construction and relative disposition as 25 to insure regularity or uniformity of operation and render the device capable of withstanding the rough handling to which barrel fillers are subjected in practical use, the efficient life of the device being thereby increased.

The invention resides in a barrel filler possessing the novel feature hereinafter described and claimed, and said invention will be fully understood from the following description, with reference to the accompanying drawings, in which:

Figure 1 is a central vertical section through a barrel filler constructed in accordance with and embodying my invention, the 40 device being shown as applied to a barrel and set for use in filling the same;

Fig. 2 is a vertical section through the same, taken on the dotted line 2—2 of Fig. 1;

Fig. 3 is a horizontal section through a 45 portion of the same, taken on the dotted line 3—3 of Fig. 1;

Fig. 4 is a horizontal section through the same, taken on the dotted line 4—4 of Fig. 1, and

Fig. 5 is a central vertical section through a hood or removable part of the casing of the device.

In the drawings, 10 designates the main body of the casing in one integral piece subdivided by a partition 11 to form an inlet

or valve chamber 12 and an outlet chamber 13, and said body 10 is formed at one side with an integral externally threaded nipple 14 for connection with the piping leading from the supply tank or reservoir. In its 60 lower side or bottom the body 10 is formed with an internally threaded opening 15 to receive the upper externally threaded end of the filling tube or discharge nozzle 16, which is adapted to be inserted downwardly 65 through an opening or bung-hole 17 in a barrel or other receptacle 18 and is provided with a suitable adjustable support comprising, in the present instance, a nut 19 having legs 20 to engage the barrel and a binding 70 nut 21 to engage the nut 19.

In its top, the body 10 is formed with an internally threaded opening 22 to receive an externally threaded plug 23 having formed within it a vertical recess 24 which is open 75 at its lower end and receives the coiled spring 25 and the upper portion of the stem 26 of the disk valve 27, said valve being located in the aforesaid chamber 12. The valve stem 26 is chambered in its upper end to receive 80 the lower end of the spring 25.

The partition 11 has an opening 28 surrounded along its upper edge by a vertical annular flange 29 affording a seat for the valve 27, whose lower surface is cupped and 85 at its annular lower edge fits upon said seat.

The body 10 is formed with a laterally extending section 30 having a top 31 and an internally threaded side opening 32 to receive a threaded plug 33, which is bored to afford 90 a bearing for one end of a horizontal shaft 34 whose other end is mounted in a bearing 35 formed as an integral part of the body 10. The shaft 34 has a crank portion 36 which pivotally receives the lower end of an arm 95 37 whose upper end enters a recess in the bottom of the valve 27 and supports said valve in a well known manner.

The shaft 34 has a polygonal outer end 38, upon which is mounted a bell-crank 39 (Fig. 100 2) whose lower arm 40 extends downwardly and is weighted or made heavier than its upper arm 41, which is hook-shaped at its upper end, as at 42. The bell-crank 39 constitutes a tripping lever and co-operates with 105 a float lever 43 which is pivotally mounted at about its middle upon a lug 44 cast integrally with the aforesaid top 31. The lever 43 is reasonably broad and is recessed out in its lower side to pass upon the lug 44, 110

and at its inner end said lever 43 is formed with a foot 45, while at its outer end said lever is reduced in width to form a finger 46 adapted to be engaged by the hook 42 of the tripping lever, as shown in Fig. 2, said finger 46 having one vertical edge to engage the inner vertical edge of the outer end of said hook and said finger at its opposite edge being beveled to permit the ready passage of the hook over said finger when said hook is moved to its operative position shown in Figs. 1 and 2.

Within the lower portion of the tube or nozzle 16 is formed a cone-shaped partition 47, below which is a float chamber 48 and above which are outlet openings 49 formed in the sides of said tube or nozzle.

Within the tube 16 and chamber 13 is located a vertical stationary tube 50, whose lower end is secured within the apex of the partition 47 and whose upper end is fastened within the top 31 of the body section 30, as shown in Fig. 1. A float 51 of customary or any suitable type is mounted within the float chamber 48, and this float is connected with the lower end of a rod 52, which extends up through and above the tube 50 and has on its upper threaded end a nut 53 which seats on the upper end of said tube 50 and a binding nut 54 which engages said nut 53. The nuts 53, 54 permit of the adjustment vertically of the rod 52 and float 51. The upper end of the rod 52 is directly below and engaged by the foot 45 on the inner end 35 of the lever 43, and said rod when moved upwardly by the float 51 turns the inner end of said lever 43 upwardly and its outer end downwardly to lower the finger 46 of said lever below the hook 42 of the lever 39, thereby permitting the shaft 34 to turn under the force of the spring 25 and the weight of the valve 27, with the result that the bell-crank 39 is carried angularly to remove the hook 42 from above the finger 46 45 and the valve 27 descends upon its seat 29, cutting off the flow of oil or other liquid through the body 10 to the tube 16. When it is desired to re-set the mechanism for use, the arm 40 of the lever 39 is employed as 50 a handle for reversely turning said lever and the shaft 34, so that through the crank 36 and arm 37 the valve 27 may be moved to its upper or wide-open position and also so that the hook 42 may reengage the finger 55 46 and thereby releasably hold the valve 27 in its open position until on the next ascent of the float 51 the rod 52 again acts to tilt the lever 43 from the lever 39 and thereby frees the shaft 34 to turn and the valve 27 60 to descend to its seat 29.

The levers 39, 43 and upper end of the rod 52 are external to the body 10 and, except for the lower end of the arm 40 of said lever 39, are protected within a chamber 55 formed by said body 10 and a removable

hood 56 whose details are shown more fully in Figs. 3, 4 and 5. The hood 56 is a hollow casting of segmental outline and has a curved outer wall and opposite sides 57 and is open at its inner and bottom portions. 70 The hood 56 is adapted to be removably fitted to the body casting 10 and over the section 30 thereof and also over the levers 39, 43, as shown in Fig. 1. The body 10 is formed integrally with a lug 58 and with 75 opposite side vertical grooves 59, and the inner vertical edges of the sides of the hood 56 have vertical flanges or ribs 60 to slide downwardly into the said grooves 59 until the top of the hood seats upon the lug 58, 80 to which the hood is secured by a screw 61, said screw and the grooves 59 and ribs 60 serving to securely hold the hood in place and also to permit its convenient removal should the levers 39, 43 require attention or 85 the rod 52 need vertical adjustment. The inner edge of the top of the hood 56 is shaped to the outline of the adjacent portion of the body 10 above the lug 58, as shown in Fig. 3. The hood 56 serves to protect the 90 levers 39, 43 and upper end of the rod 52 and adjacent parts against the effects of snow, ice, rain and other weather conditions and also against the effects of rough handling of the device or the dropping of the 95 same on the floor or ground or the knocking of the same against a barrel. The parts of the device are so arranged as to make provision for the hood 56, as well as to accomplish other results. 100

The operation of the device will be understood without further detailed explanation. In Fig. 1 I illustrate the device with its parts set for use in the filling of a barrel. When the liquid in the barrel has risen to a 105 sufficient height to properly elevate the float 51, the rod 52 turns the lever 43 to lower the finger 46 below the hook 42. The valve 27 then closes, as hereinbefore mentioned, to cut off the flow to the barrel; thereafter the 110 parts of the device may be re-set for use by turning the lever 39 to reengage the lever 43 and actuate the shaft 34 to elevate the valve 27. It will not be necessary to refer to the durable character of the several parts of 115 the device and the ease with which they may be assembled and disassembled. I may add however that the presence of the hood 56 and the location of the lever 43 permits of the use of a long pin 70 for connecting 120 said lever with the lug 44 (Figs. 2 and 4), said pin not requiring to be headed and being prevented from losing its position by reason of the fact that it extends nearly 125 across the width of the hood 56 and has its ends adjacent to the sides 57 of said hood.

What I claim as my invention and desire to secure by Letters-Patent, is—

1. A barrel filler comprising a body having a laterally extending section and pro- 130

vided with an inlet, a valve-seat and an outlet nozzle extending downwardly from said lateral section, a crank-shaft extending horizontally through the length of said body and of said lateral section and above said nozzle, a self-closing valve within said body adapted to said seat and operatively associated with the crank of said shaft, a float in said nozzle having a rod extended therefrom up through said nozzle and the top of said lateral section and having thereon a stop to arrest said rod and float against undue descent, a float-lever pivotally mounted intermediate its end portions on the top of and closely adjacent to said lateral section and having on its inner end a foot freely resting upon the upper end of said float-rod, and its outer free end formed at one side 70 with a vertical edge and at its opposite side with a downwardly and outwardly inclined edge, and a lever secured intermediate its ends upon the outer end of said shaft and having a hook on its upper end to releasably engage the said outer free end of said float-lever, for holding said valve in its open position, said hook having an inner straight edge to engage the said vertical edge of said float-lever and being adapted to ride over the inclined edge of said float-lever.

10 4. A barrel filler comprising a body having a laterally extending section below the top thereof, and provided with an inlet, 85 a valve-seat and an outlet nozzle extending downwardly from said lateral section, a crank-shaft extending through said body, a self-closing valve within said body adapted to said seat and operatively associated with 90 said shaft, a float having a rod extended therefrom up through said nozzle and said lateral section, a float-lever pivotally mounted intermediate its end portions on the top of said lateral section, and having 95 its inner end engaging the upper end of said rod, a lever secured upon the outer end of said shaft and having a hook adapted to be releasably engaged with the outer end of said float-lever for holding said valve 100 in its open position, and a hood over said lateral section and covering said float-lever and adjacent parts, said body having grooves at opposite sides and said hood having side ribs to enter said grooves and 105 a top fitted to the adjacent part of said body, and said lateral section having on its top an internally threaded lug to afford a seat for said top and receive a screw for securing the hood in place.

15 5. A barrel filler comprising a body having a laterally extending section below the top thereof, and an inlet, a valve-seat and an outlet nozzle extending downwardly from said lateral section, a crank-shaft extending horizontally through the length of said body and of said lateral section and above said nozzle, a self-closing valve within said body adapted to said seat and operatively associated with the crank of said shaft, a float in said nozzle having a rod extended therefrom up through said nozzle and said lateral section, 120 a float-lever pivotally mounted intermediate its end portions on the top of said lateral section, and having its inner end engaging the upper end of said rod, a lever secured upon the outer end of said shaft and having 125 a hook adapted to be releasably engaged with the outer end of said float-lever for holding said valve in its open position, and a hood removably secured over said lateral section and float-lever and adjacent parts 130

20 2. A barrel filler comprising a body having a laterally extending section and provided with an inlet, a valve-seat and an outlet nozzle extending downwardly from said lateral section, a crank-shaft extending horizontally through the length of said body and of said lateral section and above said nozzle, a self-closing valve within said body adapted to said seat and operatively associated with the crank of said shaft, a float in said nozzle having a rod extended therefrom up through said nozzle and the top of said lateral section and having thereon a stop to arrest said rod and float against undue descent, a float-lever pivotally mounted

25 3. A barrel filler comprising a body having a laterally extending section and provided with an inlet, a valve-seat and an outlet nozzle extending downwardly from said lateral section, a crank-shaft extending horizontally through the length of said body and of said lateral section and above said nozzle, a self-closing valve within said body adapted to said seat and operatively associated with the crank of said shaft, a float in said nozzle having a rod extended therefrom up through said nozzle and the top of said lateral section and having thereon a stop to arrest said rod and float against undue descent, a float-lever pivotally mounted

and having sides which extend downwardly below said lever, the means pivotally securing said float-lever as aforesaid, being a lug on said lateral section and a pin passing 5 through said lug and lever and extending beyond the sides of the same nearly to the sides of said hood, the sides of said hood

serving to prevent said pin from losing its operative position.

Signed at New York city, in the county 10 of New York, and State of New York, this 29th day of December, A. D. 1919.

CHARLES FISK.
